(57) **CLAIM**

What is claimed is the ornamental design for a wireless footswitch, as shown and described herein.

DESCRIPTION

FIG. 1 is an elevated, perspective view of the wireless footswitch in accordance with our invention;

FIG. 2 is a front view thereof;

FIG. 3 is a side view thereof;

FIG. 4 is an opposing side view thereof;

FIG. 5 is a top view thereof; and,

FIG. 6 is a bottom view of the invention as shown FIG. 1.

1 Claim, 4 Drawing Sheets
